VACUUM CLEANER

Herbert La Mers and Maury W. Wayne, Los Angeles,
Calif., assignors to California Car Wash Systems Inc.,
Sun Valley, Calif., a corporation of California

Filed July 28, 1965, Ser. No. 86,326

Term of patent 14 years

(Cl. D9—2)

Fig. 1

FIGURE 1 is a perspective view of the front and right side of a vacuum cleaner, showing our new design; and FIGURE 2 is a perspective view of the rear and left side of the vacuum cleaner.

The top of the handle and the side portions are flat and plain.

The dominant features of our design reside in the portions shown in full lines.

We claim:

The ornamental design for a vacuum cleaner, as shown and described.
